CLAIM

The ornamental design for a simulator frame, as shown and described.

DESCRIPTION

FIG. 1 is a first side view of a simulator frame;
FIG. 2 is an opposed second side view of a simulator frame;
FIG. 3 is a rear view of a simulator frame;
FIG. 4 is a front view of a simulator frame;
FIG. 5 is a top view of a simulator frame;
FIG. 6 is a bottom view of a simulator frame;
FIG. 7 is a first rear upper perspective view of a simulator frame;
FIG. 8 is a second rear upper perspective view of a simulator frame;
FIG. 9 is a first front upper perspective view of a simulator frame;
FIG. 10 is a second front upper perspective view of a simulator frame;
FIG. 11 is a front lower perspective view of a simulator frame; and,
FIG. 12 is a rear lower perspective view of a simulator frame.
